UNITED STATES PATENT OFFICE.

JOSEPH W. LEWIS, OF PHILADELPHIA, PENNSYLVANIA, ASSIGNOR TO THE ATLANTIC
REFINING COMPANY, OF PHILADELPHIA, PENNSYLVANIA, A CORPORATION OF
PENNSYLVANIA.

PETROLEUM-TREATING APPARATUS.

Original application filed April 19, 1917, Serial No. 163,171. Divided and this application filed April 3, 1919. Serial No. 287,178.

My invention relates to apparatus for treating petroleum, petroleum distillate or petroleum residuum in any suitable way for obtaining petroleum products in general, 5 and particularly for producing light hydrocarbons, such as naphthas, gasolenes and burning or kerosene oil.

My invention resides in oil treating structure comprising a still structure, preferably vertically disposed, which is separate from the oil heating means, the latter comprising a suitable furnace in which is disposed heat absorbing oil containing structure, preferably tube connected drums, having oil connections to the still structure.

My invention resides in oil treating still structure with which is associated a condenser for oil vapors, said condenser preferably air cooled and disposed upon the still structure and having runback connections to the still.

My invention resides in oil treating apparatus of the character hereinafter described.

This application is a division from my application Serial Number 163,171, filed April 19, 1917.

For an illustration of one of various forms my invention may take, reference is had to the accompanying drawings, in which:

30 Fig. 1 is a slide elevational view, partly in section, of still structure and associated condenser.

Fig. 1^a is a fragmentary plan view of oil connections between a drum and the still.

35 Fig. 2 is a fragmentary sectional view illustrating heat transfer structure.

Fig. 3 is a fragmentary view, on enlarged scale, of the upper end of the still and associated condenser.

40 Fig. 4 is a fragmentary side elevational view, on enlarged scale, of the upper end of the still and part of the condenser structure.

Referring to Fig. 1, S is a vertical still of boiler plate, provided with the manholes 1, 1 near its bottom and top. The oil to be treated is pumped into the still through the pipe 2 until it reaches the top of the pipe 3 within the still, which serves to indicate when the proper level has been reached by 45 overflow through the pipe 3 and its control valve 4, appearance of oil at the outer and lower orifice of the pipe 3 indicating that the

proper level is reached, whereupon the valve 4 is closed.

Within the brickwork structure 5 are disposed the upper and lower cylindrical drums D and D¹, each connected at its one end by pipes 6 and 7, see Fig. 1^a, with the interior of the still 3, the pipes 6 and 7 of each pair connecting to opposite sides of the still. 55

The drums D, D¹ are connected by the numerous substantially vertical metal tubes 8, as indicated in Figs. 1 and 2.

The chamber containing the drums and their connecting tubes communicates through 65 the opening 9 with the firebox or chamber 10 in which is disposed the grate 11 on to which fuel is delivered from the chute 12 through the hopper or stoker 13, the ashes falling into the pit 14 and delivered there- 70 from to ash-removing cars 15.

In the chamber containing the drums D, D¹ and the tubes 8 are the baffles 16, Fig. 2, with the result that the hot gases pass from the firebox or chamber 10 through the opening 9, and between and around the upper parts of the tubes 8 and the drum D and pass downwardly in contact with the lower parts of the tubes 8 and the drum D¹ and thence into the flue passages 17, 17, Fig. 2, 80 which communicate with a stack or chimney, not shown, which may be common to several stills. Communicating with the interior of the chamber containing the drums and tubes is a stack 18 having the closing cover 19, 85 which latter may be moved to open position to allow escape of hot gases from the chamber, either in a measure to control the temperature to which the tubes 8 and drums D, D¹ are subjected, or rapidly to cool the 90 chamber at the end of a run.

At the upper end of the still S is the vapor outlet pipe 20, Figs. 1 and 4, communicating through valve 21 with the sweat out line or pipe 22, and with the pipe 23 leading to 95 the safety valve 24 whose discharge side communicates with the vertically extending pipe 25. The main vapor line 20 communicates also through the valve 26 with the upwardly and then downwardly extending 100 vapor line or pipe 27 which communicates with the initial manifold or header 28 communicating with the three transversely extending initial header pipes 29 with which

communicate the numerous small vertically extending pipes 30 connected in various groups through the top connecting pipes 31 with the numerous small downwardly extending pipes 32 communicating with the transverse terminal header pipes 33 which all communicate with the terminal header or manifold 34. The numerous pipes 30 and 32, and associated connections, are housed within the structure 35 open at its bottom and having at its top an open-work cover 36 of wire mesh or the like.

These pipes 30, 32 and their connections constitute means for preliminarily cooling the vapors rising from the still S and constitute the preliminary air cooled condenser, the cooling air entering at the bottom of the housing 35 and passing upwardly between the tubes 30, 32 and out through the open-work cover 36.

From transverse header pipes 29 and 33 extend downwardly the several pipes 37, Figs. 1 and 3, which communicate at their lower end with a pipe 38 with which is connected the riser pipe 39 controlled by valve 40 and communicating with the interior of the still S at its top, this piping structure constituting a runback whereby there are returned into the still S those heavy oils whose vapors have been condensed in the air condenser and which have been only partially, if at all, subjected to the desired treatment.

Referring now more particularly to Fig. 3, there is connected with the header 34 of the air condenser a pipe 41, to which is connected the tell-tale pipe 42 controlled by valve 43, communicating through the valve 44 and the pipe 45 with the intake of the reducing valve 46 whose outlet communicates through the pipe 47 and the valve 48 with the vapor line or pipe 49. The pipes 41 and 49 are also connected through the normally closed by-pass valve 50.

The pressure-reducing means may be of any suitable type, a Watson reducing valve having been found satisfactory in operation.

A pressure gauge 69 is connected by pipe 66 with the pipe 41 through the hand operated valve 68 and also through the hand operated valve 67 with a chamber of the control mechanism of the reducing valve 46.

The operation is as follows:

The oil to be treated is charged into the still S to a level corresponding to the upper end of the pipe 3, the drums D and D¹ and their connecting pipes being simultaneously charged by oil rising through the lower connecting pipes 6 and 7 into the drum D¹ and thence rising through the fire tubes 8 into and filling the drum D and its pipes 6 and 7 connecting at a higher level with the still S.

The valves 26, 40 and 50 are closed. Fire is started in the furnace chamber 10 and the charged oil gradually raised in temperature, the valve 21 in the sweat-out line 22 being

open, no substantial pressure being produced within the still. As the charge rises in temperature, the water entrained therein is vaporized into steam and passes off through the pipe 20, valve 21 and sweat-out line 22 to a slop tank, not shown. After the water has so been driven off, the valves 26 and 40 are open, and valve 21 closed.

The firing is continued and the temperature of the oil in the still increases, the pressure within the still simultaneously increasing until suitable magnitude of pressure is reached for which the reducing valve 46 is set; thereupon the valve 46 allows escape of vapors from pipe 45 to the pipe 49, valves 44 and 48 being open. The vapors of heavy oils which may pass from the still S to the air condenser are therein condensed and returned to the still S through the runback connections 37 and 39 through the now open valve 40.

The lighter vapors of the desired products are not condensed in the air condenser, but pass off through the reducing valve 46 and pipe 49 to a main or water cooled condenser, not shown, or to any other suitable device or desired destination.

The firing is continued until the oil in the still S has been reduced to a residuum of suitable or desired percentage of the volume of the original charge. To determine when this stage is reached, the valve 101, Fig. 1, is opened from time to time, and when for the first time vapor is delivered through the water cooled pipe coil 102 through its outlet 100 103, it is known that the charge has been sufficiently reduced and has reached a level corresponding with the upper end of the pipe 104 communicating through the valve 101 with the coil 102.

At the end of a run the fire is withdrawn, the reducing valve 46 is by-passed by closing valves 44 and 48 and opening valve 50, whereupon the gas and vapor contents of the still pass therefrom through the air condenser, thence through the valve 50 to the vapor pipe or line 49, and led to a suitable condenser or other desired destination.

When the pressure in the still has been entirely reduced or released, the residuum in the still S is pumped out. To free the still of vapors and gases before entry of cleaners, steam is admitted through pipes 109, 110, 111 and 112, Fig. 1, each controlled by a valve 113. Valve 21 is opened to allow escape of vapors and gases driven out by the entering steam through sweat-out line 22.

After the removal of residuum and the blowing off of vapors and gases as above described, the still S may be entered through either manhole 1, and any deposits therein, as of coke or carbonaceous material, removed through the lower manhead 1. Similarly, the drums D, D¹ may be entered through the manholes d and d¹ and similarly cleaned

of carbonaceous material or coke. Deposits of carbonaceous material or coke within the fire tubes 8 may be removed by devices similar to boiler tube cleaners.

5. What I claim is:

1. Pressure still structure comprising a plurality of substantially horizontal drums disposed at different levels, a plurality of tubes connecting said drums, a heating chamber in which said drums and tubes are disposed, a still outside of said heating chamber extending from adjacent a lower of said drums to and materially above an upper of said drums, circulating connections between said lower and upper drums and said still, and a vapor discharge line connecting with said still above the liquid level therein.
2. Pressure still structure comprising a plurality of substantially horizontal drums disposed at different levels, a plurality of tubes connecting said drums, a heating chamber in which said drums and tubes are disposed, a still outside of said heating chamber extending from adjacent a lower of said drums to and materially above an upper of said drums, circulating connections between said lower and upper drums and said still, a vapor discharge line connecting with said still above the liquid level therein, and means for charging oil to be treated into said still.

3. Petroleum cracking apparatus comprising a heating chamber, a still outside of said heating chamber, drums in said heating chamber, substantially vertical tubes in said chamber and connecting said drums, and branched oil circulating connections between each of said drums and said still.

4. Petroleum cracking apparatus comprising a heating chamber, a vertical still disposed outside of said chamber, drums in said chamber, substantially vertical tubes in said chamber connecting said drums, and branched oil circulating connections between each of said drums and said still, the connections from said drums connecting with said still at different heights.

5. Petroleum cracking apparatus comprising a vertical still, and separate means for communicating heat to the petroleum and causing circulation thereof comprising drums disposed at different levels and having circulating connections with the interior of said still, a plurality of tubes connecting said drums and constituting part of the circulatory system, a housing separate from said still for said drums and tubes, means within said housing for imparting heat to said tubes, and means for discharging vapors from the upper end of said still from a vapor space whose lower limit is materially above the upper circulating connection.

6. Petroleum cracking apparatus comprising

ing a vertical still, and separate means for communicating heat to the petroleum and causing circulation thereof comprising drums disposed at different levels and having circulating connections with the interior of 70 said still, the uppermost of said connections connecting with said still at a level materially below the top of said still, a plurality of tubes connecting said drums and constituting a part of the circulatory 75 system, a housing separate from said still for said drums and tubes, and means within said housing for imparting heat to said tubes.

7. Petroleum cracking apparatus comprising a vertical still, and separate means for communicating heat to the petroleum and causing circulation thereof comprising drums disposed at different levels, and branched 80 circulating connections between each of said drums and the interior of said still, the uppermost of said connections connecting with said still at a level materially below the top of said still, a plurality of tubes connecting 85 said drums and constituting a part of the circulatory system, a housing separate from said still for said drums and tubes, and means within said housing for imparting heat to said tubes.

8. Pressure still apparatus for treatment of petroleum comprising a vertical still, heat transfer structure separate therefrom and having circulating connections therewith, said still extending substantially higher than the uppermost of said circulating connections, whereby said heat transfer structure is completely filled and said vertical still to a level materially above said uppermost circulating connection is filled with the oil under treatment, a vapor outlet from 90 said still above the uppermost of said circulating connections, and means for maintaining the petroleum in said separate heat transfer structure under pressure comprising a valve restricting the discharge of vapor 95 from said still through said vapor outlet.

9. Pressure still apparatus for treatment of petroleum comprising a vertical still, heat transfer structure separate therefrom and having circulating connections therewith, said still extending substantially higher than the uppermost of said circulating connections, a condenser surmounting said still and having a vapor connection therewith, a runback connection from said condenser to said still separate from said vapor connection, and means for maintaining the petroleum in said separate heat transfer structure under pressure comprising a valve 100 restricting discharge from the outlet from said condenser.

10. Petroleum treating apparatus comprising a vertical still, an air-cooled condenser disposed directly above the upper end of said still, a vapor connection from said

still to said condenser, a vapor outlet connection from said condenser, descending-ascending runback connections from said condenser into said still, and means for maintaining pressure upon the apparatus.

11. Petroleum treating apparatus comprising a vertical still, an air-cooled condenser disposed directly above the upper end of said still, a vapor connection from said still to said condenser, a vapor outlet connection from said condenser, and a valve restricting flow of vapor from said condenser, whereby the vapor in said condenser and the oil in said still are maintained under pressure.

12. Petroleum treating apparatus comprising a vertical still, an air-cooled condenser disposed above the upper end of said still, a vapor connection from said still to the condenser, a vapor outlet connection from the condenser, a pressure reducing valve controlling said outlet connection, valve structure for by-passing said reducing valve, and a valve controlled runback from said condenser into said still.

13. Petroleum treating apparatus comprising a vertical still, an air-cooled condenser disposed above the upper end of said still, a vapor connection from said still to said condenser, a vapor outlet connection from said condenser, a pressure reducing valve controlling said outlet connection, valve structure for by-passing said reducing valve, a valve controlled runback from said condenser into said still, and connections for blowing steam into said still.

14. Petroleum treating apparatus comprising a vertical still, an air-cooled condenser, a vapor connection from said still to said condenser, a vapor outlet connection from said condenser, a pressure reducing valve controlling said outlet connection, valve structure for by-passing said reducing valve, a valve controlled runback from said condenser into said still, and a valve controlled sweat-out line connecting with said still.

15. Petroleum treating apparatus comprising a vertical still whose height is several times its diameter, heat transfer structure separate from said still, means for maintaining the oil in said structure under pressure, connections from said structure to said still one of which is adjacent the bottom of said still and another at a substantially higher level materially below the upper end of said still, and a vapor outlet at a level above said other connection.

16. Petroleum cracking apparatus comprising a vertical still whose height is several times its diameter; means for delivering heat to the charge comprising connections adjacent the bottom of said still and at a substantially higher level materially below the upper end of said still, a vapor out-

let at a level above said higher level, and means for maintaining in said still a pressure materially above atmospheric pressure.

17. Petroleum cracking apparatus comprising a vertical still whose height is several times its diameter, means for delivering heat to the charge comprising connections adjacent the bottom of said still and at a substantially higher level materially below the upper end of said still, an air-cooled condenser disposed above said still, a vapor connection between said still and condenser from a level in said still above said higher level, and means for maintaining in said still and condenser a pressure materially above atmospheric pressure.

18. Apparatus for cracking petroleum under pressure, comprising a heating chamber, a vertical still having a height several times its diameter disposed outside of said heating chamber, drums disposed at different heights in said heating chamber, tubes in said chamber connecting said drums, and oil circulation connections between said drums and said still, said still having a vapor space whose lower limit is above the uppermost of said drums.

19. Apparatus for cracking petroleum under pressure, comprising a heating chamber, a still having a height several times its diameter disposed outside of said heating chamber, drums at different levels in said heating chamber, a plurality of tubes connecting said drums, and circulating connections between said drums and said still at different levels, the oil partaking of natural circulation through said still, drums and tubes due to temperature effects, said still having a vapor space whose lower limit is above the uppermost of said connections.

20. Apparatus for cracking petroleum under pressure, comprising a vertical still having a height several times its diameter, heat transfer structure for imparting heat to the oil comprising drums at different levels, the interior of each of said drums being unrestricted to form a single compartment, a plurality of tubes connecting said drums, and connections from said drums to said still at different levels, said still extending materially above the uppermost of said connections, the oil always passing in the same direction from a lower drum through the tubes to an upper drum, and from said upper drum to said still before return to said lower drum.

21. Apparatus for producing lighter from heavier hydrocarbon oil comprising a vertically extending chamber of large cross section for confining a column of oil, means for passing oil in a plurality of streams of small cross section from said column back to said column at a higher submerged level thereof, said column having great vertical

extent above said higher submerged level, means for applying heat to said streams at a rate to effect cracking of the oil in a zone from which said column of oil is isolated, and means for drawing off vapors at the upper end of said column.

22. Apparatus for producing lighter from heavier hydrocarbon oil comprising a vertically extending chamber of large cross section for confining a column of oil, means for passing oil in a plurality of streams of small cross section from said column back to said column at a higher submerged level thereof, said column having great vertical extent above said higher submerged level, means for applying heat to said streams at a rate to effect cracking of the oil in a zone from which said column of oil is isolated, means for maintaining the oil under super-atmospheric pressure, and means for drawing off the products at the upper end of said column.

23. Pressure still structure comprising a housing for oil-heating structure, a still chamber entirely separate from said housing on the exterior thereof, said still chamber containing a mass of liquid oil disposed in a single body, oil-heating structure disposed entirely within said housing and comprising a plurality of substantially horizontal chamber structures disposed at different levels within said housing and throughout each of which the oil is of substantially uniform composition, circulating connections extending from upper and lower chamber structures, respectively, to the body of oil in said still chamber, and a plurality of substantially vertical tubes connecting said chamber structures within said housing, said chamber structures, tubes and connections constituting a path through which the oil is repeatedly circulated from the body of oil in said still chamber through the lower of said connections, lower chamber structure, upwardly through all of said tubes, through the upper of said chamber structures, and back to said body of oil in said still chamber, in the order named.
